205,899

COMBINED FINGER RING AND SHOOTING TOY

Jack Zimmerman, Roaring Brook Lake,
Putnam Valley, N.Y.

Filed Oct. 15, 1965, Ser. No. 87,519

Term of patent 14 years

(Cl. D34—15)

FIG. 1 is a perspective view of a combined finger ring and shooting toy showing my new design.

FIG. 2 is a top view thereof.

FIG. 3 is a front view thereof.

FIG. 4 is a perspective view thereof showing the projectile in separated position.

I claim:

The ornamental design for a combined finger ring and shooting toy, as shown.

References Cited by the Examiner

UNITED STATES PATENTS

1,988,191	1/1935	Donato	-----	124—6
2,642,058	6/1953	Murphy	-----	124—6

OTHER REFERENCES

Premium Practice, January 1951, page 104, Custom Premiums by Leavens Mfg. Co., rings.

EDWIN H. HUNTER, Primary Examiner.

MELVIN FEIFER, Assistant Examiner.